ELECTRON BEAM CENTERING SYSTEM

Hans W. G. Salinger and Albert T. Mayle, Jr.,
 Fort Wayne, Ind., assignors, by mesne assignments,
 to Farnsworth Research Corporation, a corporation of Indiana

Application November 6, 1946, Serial No. 708,004

7 Claims. (Cl. 315—18)

1

This invention relates to systems for controlling an electron beam and has particular reference to voltage distributing systems for impressing beam orienting voltages on the field producing electrodes of a cathode ray tube.

According to conventional practice, wherever it is desired to deflect an electron beam over a target electrode, it is necessary, not only to produce a field of substantially uniform intensity which is varied periodically in magnitude to effect the desired beam deflection, but also to produce a second relatively constant field of uniform intensity, so as to suitably orient the beam relative to the target electrode. Usually the field-producing facilities of the tube have impressed thereon substantially constant unidirectional voltages or currents in suitable magnitudes to produce the beam-orienting field. In addition these field-producing facilities have impressed thereon the deflecting voltages or currents, which in a sense, are superimposed upon the constant unidirectional voltages or currents.

Where the cathode ray tube is one such as a television image dissector the electron beam has a cross-section of considerable magnitude. Heretofore, it has been the general practice to orient and deflect such a beam relative to a target electrode by means of electromagnetic fields. However, it also has been proposed to produce such a field electrostatically. One such device operating on this latter principle, is disclosed in Patent No. 2,297,949, granted to P. T. Farnsworth on October 6, 1942, for a Deflecting system. In one embodiment of the patented structure, the field-producing electrodes are in the form of elongated rods or stiff wires, a number of which are placed in spaced positions around the path of the beam so that each of the electrodes extends generally longitudinally of the electron beam path. The high frequency and low frequency deflecting voltages are impressed upon these electrodes by means of a voltage distribution network of such a character that each of the electrodes has impressed thereon a voltage which in magnitude is proportional to the voltages impressed upon the other electrodes in accordance with its particular location relative to two coordinate scanning directions. The voltage distributing network is energized by the two deflecting voltages which vary periodically in magnitude according to the particular scanning pattern desired. Usually for analyzing a television image the deflecting voltages have substantially saw-tooth wave forms.

In a device such as that disclosed in the Farnsworth patent referred to, the so-called centering

2

voltage or the voltage by means of which the electron beam is suitably oriented relative to the target electrode most conveniently is impressed upon the elongated field-producing electrodes.

- 5 Inasmuch as the field which it is desired to produce for orienting the beam relative to the target electrode is not required to vary in its intensity, the centering voltages impressed upon the electrodes are unidirectional voltages of relatively constant magnitude. These centering voltages must also be impressed upon the respective electrodes in suitable magnitudes according to the location of the electrodes relative to the direction of the beam-centering field in order that this field shall be homogeneous and of substantially uniform intensity.

One general form of system for producing a beam-centering field in a tube of the character disclosed in the Farnsworth patent referred to is disclosed in the co-pending application of H. W. G. Salinger, Serial No. 701,722, filed October 7, 1946, and entitled "Electron beam controlling system." According to this system a voltage distribution network is employed to impress centering voltages upon the field-producing electrodes, whereby the electron beam may be shifted independently in either of two coordinate directions. Such a system requires that the voltage distribution network be energized at two pairs

- 20 of input terminals. In order to shift the electron beam in one coordinate direction a voltage varying device is required between the source of energy for the distribution network and one pair of input terminals, and a similar device is required for the other pair of input terminals. Regardless of whether one or two sources of energy are used to energize such a distribution network, there is a considerable power loss inherent in the operation of such a system.
- 25
- 30
- 35

40 It is, therefore, one of the objects of this invention to provide a novel voltage distribution system for orienting an electron beam of a cathode ray tube relative to a target electrode with a minimum loss of power.

- 45 Another object of the invention is to provide an electron beam-centering voltage distributing system which utilizes only one relatively simple network.

50 Still another object of the invention is to provide a novel system for centering an electron beam which functions on a polar rather than a rectilinear coordinate basis.

In accordance with the present invention, there is provided a cathode ray tube which has facilities for developing an electron beam and direct-

ing it toward a target electrode. The tube also is provided with a plurality of field producing electrodes located in spaced positions around the path of the beam. These electrodes, when energized by suitable voltages in accordance with the invention, produce an electrostatic field of substantially uniform intensity and constant magnitude, whereby the beam normally is directed toward a predetermined point on the target electrode. The voltages for effecting the production of the beam-orienting field are impressed upon the electrodes by a voltage distributing network in accordance with an important feature of the invention. This network is designed so as to derive from a source of unidirectional voltage a predetermined voltage distribution pattern for the electrodes, whereby to provide a uniformly distributed field. The voltage distributing network is connected to the field-producing electrodes of the tube by means of a switch which is operable to effect a cyclical permutation of the electrodes with respect to the voltage distribution pattern, whereby to rotate the direction of the field about the longitudinal axis of the tube. There also are provided means for varying the magnitude of the voltage by which the voltage distributing network is energized so that the strength of the field may be varied as desired.

For a better understanding of the invention, together with other and further objects thereof, reference is made to the following description, taken in connection with the accompanying drawing, and its scope will be pointed out in the appended claims.

In the accompanying drawing:

Fig. 1 is a longitudinal sectional view of a television image dissector tube having a plurality of electrodes, whereby to effect electrostatic deflection of electron beam relative to a target electrode; and,

Fig. 2 is a schematic circuit diagram of apparatus embodying the invention, whereby suitable deflecting and centering voltages are impressed upon the tube deflecting electrodes.

Having reference now to Fig. 1 of the drawing, there is shown a television image dissector tube 11. One end wall of the tube is provided with an optically plane window 12, and there is mounted adjacent to the other end of the wall of the tube a photoelectric cathode 13. The photosensitive surface of the cathode faces the window 12 so that an optical image may be projected through the window onto the cathode. The tube also is provided with a target electrode 14 located at one end thereof adjacent the window 12. The target electrode is provided with a relatively small aperture 15, substantially of the size of an elemental area of the picture which it is desired to analyze. Preferably the aperture is located on the central axis of the tube. In any case, it faces the cathode 13, so that electrons from the cathode may enter the target electrode through the scanning aperture 15. In accordance with generally preferred practice, the target electrode 14 serves as a housing for an electron multiplier, whereby a preliminary video signal amplification may be effected. The target electrode also is maintained at a positive potential relative to the cathode by means such as a battery 16.

The tube 11 also is provided with a plurality of elongated deflecting electrodes such as the wires or rods 17. In the embodiment of the invention disclosed herein the tube is provided with twelve of such electrodes uniformly spaced around the inside periphery of the envelope. These electrodes

5 extend parallel to the longitudinal axis of the tube and preferably from the plane of the cathode 13 to a plane adjacent to the scanning aperture 15 of the target electrode 14. Each of the electrodes is connected through the tube envelope by means, such as a conductor 18. In this manner electrical connections may be made to each of the electrodes. An electrically conducting wall coating 19 is formed on the inside of the tube envelope. 10 This wall coating may be connected to the anode 14, as shown.

The tube is also provided with an electron focusing device such as an electromagnetic coil 20 which is mounted around the exterior portion 15 of the tube envelope in such a manner that it substantially completely encloses the space between the cathode 13 and the target electrode 14. The focusing coil may be energized from a suitable source of unidirectional voltage such as a battery 21 which may be connected to the coil through an adjustable resistor 22. By means of this resistor the magnitude of the current flowing through the focusing coil may be varied so as to effect the desired focusing of the electron beam.

25 The electrical connections to the field producing electrodes such as 17 are indicated in Fig. 2 to which reference will now be made. In the drawing which includes a transverse sectional view of the image dissector tube 11, there are shown completely the connections between each of the tube electrodes and the voltage distributing system, whereby beam orientation is obtained. Inasmuch as the facilities required for the impression of the deflecting voltages upon these electrodes 30 forms no part of the instant invention, the connections to the tube electrodes for this purpose have been shown only diagrammatically.

Each of the field-producing electrodes of the tube is connected through one of a plurality of resistors 23 to one of a plurality of contacts of 40 a multi-pole multi-position switch 24. This switch is also provided with contact arms which are connected to suitable taps on a voltage divider 25. The voltage divider comprises a series 45 connection of a plurality of resistors such as 26 and 27 having impedance values suitable to provide the desired distribution of the energizing voltage. The voltage divider is energized from a source of unidirectional voltage such as a battery 28. Two potentiometers, 29 and 31 are connected to the terminals of the battery 28. The sliding contact 32 of the potentiometer 29 is connected through a resistor 33 to one terminal of the voltage divider 25. The sliding contact 34 of 50 the other potentiometer 31 is connected through a resistor 35 to the other terminal of the voltage divider.

55 The particular form of the switch 24 which is employed in practicing the invention is immaterial. Many switches for the purpose are well known in the art and no attempt is made in the instant disclosure to indicate any particular type of switch. The arrangement shown is purely diagrammatical and is for the purpose of illustrating the invention in the simplest possible manner. As shown, the switch 24 comprises a plurality of contacts, such as 36, equally spaced in a circular pattern. There also are provided an equal number of contact arms, such as 37, designed to engage any one of the contacts such as 36. Connections are made between the contact arms and the taps on the voltage divider by any suitable means. For example, a connection is made from the voltage divider tap 38 at the junction point of resistors 70 26 and 27 to the contact arm 37 by means of a

conductor 39. Similar connections are made to the other contact arms of the switch as shown. Two of the contact arms 41 and 42 are connected respectively to the terminals of the voltage divider 25. The other contact arms are connected in pairs to the intermediate taps on the voltage divider. For example, the contact arm 37 and the contact arm 43 are connected together internally of the switch, whereby both are connected by the conductor 39 to the voltage divider tap 38.

For the impression of the deflecting voltage upon the field producing electrodes such as 17 of the tube 14, couplings are provided from the respective electrodes to a voltage distribution system for the deflecting voltages. For example, the electrode 44 is coupled by a condenser 45 to the deflecting voltage distributing network 46. The high frequency deflecting voltage source 47 is coupled to two terminals of the distribution network and the low frequency deflecting voltage source 48 is connected to another pair of input terminals of the distribution network. Both of these deflecting voltages vary periodically in a saw-tooth wave manner, whereby the voltages derived from the network 46 for impression upon the tube electrodes are varied according to a saw-tooth form. The voltage distribution network 46 has the characteristic of properly proportioning the saw-tooth voltages so that they are impressed upon the tube electrodes in proper magnitudes to produce a deflecting field of substantially uniform intensity.

Referring now to the operation of the voltage distributing system in accordance with the present invention, assume that it is desired to center the electron beam at the scanning aperture of the anode electrode. Also assume that the scanning aperture is located on the longitudinal axis of the tube. Assume also that the electron beam is initially centered below and to the left of the longitudinal axis of the tube as it is viewed in Fig. 2. In such a case the switch 24 is manipulated so as to effect such a movement of the contact arms relative to the contacts of the switch that the positions are as shown in the drawing. In such a case the contact arm 42 by its engagement with the contact 49 connects the lower terminal of the voltage divider 25 to the tube electrode 51. At the same time the contact arm 41 by its engagement with the contact 52 connects the upper terminal of the voltage divider to the tube electrode 53. In this manner the voltage of greatest magnitude which may be derived from the voltage divider 25 is connected to the diametrically opposed electrodes 51 and 53. The voltages which are impressed upon all other electrodes of the tube are of lesser magnitudes by reason of the connections of these electrodes through the switch 24 to intermediate taps on the voltage divider. Electrodes 54 and 55 are connected to the center tap 56 of the voltage divider and, therefore, are at zero potential. It may be seen, therefore, that the field which is produced by the tube electrodes for orienting the electron beam is angularly directed relative to the vertical axis of the tube, so that it extends along the line joining the electrodes 51 and 53. If now the sliders 32 and 34 of the potentiometers 29 and 31 respectively are moved downwardly below the center points of the potentiometers, a positive potential will be impressed upon electrode 53 and an equal negative potential will be impressed upon the electrode 51. The other tube electrodes will have positive and negative potentials impressed thereon to produce the desired field which will tend to shift the electron beam upwardly along the line joining the elec-

trodes 51 and 53. The magnitude of the beam shift will depend upon the magnitude of the centering voltages applied to the tube electrodes. These are regulated by the potentiometers 29 and 31.

It may be seen from the foregoing description of an illustrative embodiment of the invention that the direction of the beam centering field is determined by the position of the switch 24. The strength of this field may be varied by the potentiometers 29 and 31. The effect of such a system is to produce a beam centering facility which operates on the basis of polar coordinates in contrast to more conventional systems operating on the basis of rectilinear coordinates. An advantage of such a system is that there is no need to provide a complex voltage distribution network, such as that disclosed in the co-pending Salinger application referred to where the beam centering is effected according to rectilinear coordinates. In a system embodying the present invention only one voltage varying piece of apparatus is required. Consequently, the power losses inherent in the use of such devices are considerably lower. In general, it is seen that the voltage divider 25 is an illustrative embodiment of a voltage distributing network for deriving from a source of unidirectional voltage a predetermined voltage distribution pattern for the field-producing electrodes. The switch 24 is one device for effecting a cyclical permutation of the electrodes with respect to the voltage distribution pattern. That is, the electrodes may be shifted in their connections to the network without changing the order or sequence of the electrodes.

While there has been described what at present is considered the preferred embodiment of the invention, it will be obvious to those skilled in the art that various changes and modifications may be made therein without departing from the invention, and it is aimed, therefore, in the appended claims to cover all such changes and modifications as fall within the true spirit and scope of the invention.

What is claimed is:

1. A system for orienting an electron beam relative to a target electrode comprising, a plurality of field-producing electrodes located in spaced positions around the path of said beam, a source of unidirectional voltage, a voltage distributing network for deriving from said source a predetermined voltage distribution pattern for said electrodes, a switch for connecting said electrodes to said voltage distributing network and adapted to effect a cyclical permutation of said electrodes with respect to said voltage distribution pattern, whereby to secure any one of a plurality of angular directions of the field produced by said electrodes in the path of said beam, and means to vary the magnitude of the voltage impressed upon said voltage distributing network from said source, whereby to correspondingly vary the strength of said field.

2. A system for orienting an electron beam relative to a target electrode comprising, a plurality of elongated field-producing electrodes located in spaced positions around the path of said beam, a voltage distributing network, a switch connecting said field-producing electrodes to said voltage distributing network, said switch being adapted to connect said electrodes to any one of a plurality of different voltage points on said voltage distributing network, whereby to secure any one of a plurality of angular directions of the field produced by said electrodes in the path of

said beam, and means to variably energize said voltage distributing network, whereby to correspondingly vary the strength of said field.

3. A system for orienting an electron beam relative to a target electrode comprising, a plurality of elongated field-producing electrodes located in spaced positions around the path of said beam, a voltage distributing network, a multipole multi-position switch connecting said field-producing electrodes to said voltage distributing network, said switch being operable to change the connections of said electrodes to said voltage distributing network so as to shift the angular direction of the field produced by said electrodes in the path of said beam, a source of unidirectional voltage coupled to said voltage distributing network, and means to vary the magnitude of the voltage impressed upon said voltage distributing network, whereby to correspondingly vary the strength of said field.

4. A system for orienting an electron beam relative to a target electrode comprising, a plurality of elongated field-producing electrodes located in spaced positions circularly around the path of said beam, a voltage distributing network having a plurality of different voltage taps, a switch having two sets of contacts, means for connecting one set of said switch contacts respectively to said field-producing electrodes, means for connecting the other set of said switch contacts to said voltage distributing network taps, one set of said switch contacts being operable relative to the other set of said contacts to change the connections of said electrodes to said voltage distributing network taps so as to shift the angular direction of the field produced by said electrodes in the path of said beam, a source of unidirectional voltage coupled to said voltage distributing network, and means to vary the magnitude of the voltage impressed upon said voltage distributing network, whereby to correspondingly vary the strength of said field.

5. A system for orienting an electron beam relative to a target electrode comprising, a plurality of elongated field-producing electrodes located in spaced positions circularly around the path of said beam, a voltage divider having a plurality of different voltage taps, a switch having two sets of contacts each equal in number to the number of said field-producing electrodes, means for connecting one set of said switch contacts respectively to said field-producing electrodes, means for connecting the other set of said switch contacts to said voltage divider taps, one set of said switch contacts being operable relative to the other set of said contacts to change the connections of said electrodes to said voltage divider taps so as to shift the angular direction of the

field produced by said electrodes in the path of said beam, a source of unidirectional voltage coupled to respective terminals of said voltage divider, and means to vary the magnitude of the voltage impressed upon said voltage divider, whereby to correspondingly vary the strength of said field.

6. A system for orienting an electron beam relative to a target electrode comprising, a plurality of elongated field-producing electrodes located in spaced positions circularly around the path of said beam, a voltage divider having a plurality of different voltage taps, a switch having a set of stationary contacts and a corresponding set of movable contacts equal in number to the number of said field-producing electrodes, means for connecting one set of said switch contacts respectively to said field-producing electrodes, means for connecting the other set of said switch contacts to selected ones of said voltage divider taps, said movable switch contacts being operable relative to said stationary contacts to change the connections of said electrodes to said voltage divider taps so as to shift the angular direction of the field produced by said electrodes in the path of said beam, a source of unidirectional voltage, and means including a pair of voltage varying devices for coupling said voltage source to respective terminals of said voltage divider, said voltage varying devices being adjustable to vary the magnitude of the voltage impressed upon said voltage divider, whereby to correspondingly vary the strength of said field.

7. A system for orienting an electron beam relative to a target electrode comprising, a plurality of elongated field-producing electrodes located in spaced positions circularly around the path of said beam, a voltage divider having a plurality of different voltage taps, a switch having a plurality of contacts and a corresponding number of movable arms equal in number to the number of said field-producing electrodes, means for connecting said switch contacts respectively to said field-producing electrodes, means for connecting said switch arms to selected ones of said voltage divider taps, said switch arms being operable relative to said contacts to change the connections of said electrodes to said voltage divider taps so as to shift the angular direction of the field produced by said electrodes in the path of said beam, a source of unidirectional voltage, and means including a pair of potentiometers for coupling said voltage source to respective terminals of said voltage divider, said potentiometers being adjustable to vary the magnitude of the voltage impressed upon said voltage divider, whereby to correspondingly vary the strength of said field.

HANS W. G. SALINGER.
